[57] CLAIM

The ornamental design for a headband or the like, as shown and described.

DESCRIPTION

FIG. 1 is a front perspective view of a headband or the like showing my new design; the showing of a headband in broken lines is for illustrative purposes only; FIG. 2 is a left side elevational view thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a right side elevational view thereof;

FIG. 8 is a front perspective view of another embodiment of the headband or the like shown in FIG. 1;

FIG. 9 is a left side elevational view thereof;

FIG. 10 is a top plan view thereof;

FIG. 11 is a front elevational view thereof;

FIG. 12 is a rear elevational view thereof; and

FIG. 13 is a right side elevational view thereof.
